UNITED STATES PATENT OFFICE.

BENJAMIN ROMAN, OF NEW YORK, N. Y.

WINDOW-SASH LOCK.

Application filed June 9, 1923. Serial No. 644,385.

To all whom it may concern:

Be it known that I, BENJAMIN ROMAN, a citizen of the United States, and resident of the city of New York, in the county of Bronx and State of New York, have invented a certain new and useful Window-Sash Lock, of which the following is a specification.

This invention relates to sash locks that are primarily intended for locking window sashes in any partially opened position in the type of windows wherein an upper and a lower sash guided in ways are slidable upwardly and downwardly for opening and closing the window.

The principal object of my invention is to provide a simplified, inexpensive, strong, durable, and improved sash lock that can be economically manufactured and sold at low cost, that can be conveniently and rapidly installed by the purchaser, and that can be operated conveniently and efficiently after installation to lock the sashes, to be rendered inoperative, and to prevent unlocking thereof by a burglar or intruder reaching thereto with an implement from the exterior, for the purpose of unlocking the sashes.

Another object of the invention is to provide the above lock with means whereby it may be set out of and into operative state by the mere pressure upon and withdrawal of, respectively, a plunger, whereby it will remain set in its inoperative state upon said pressure of the plunger, and whereby it may be locked in its operative state by a threading manipulation of the same plunger.

Other objects and advantages will hereinafter appear.

In the accompanying drawings,—

Fig. 1 shows a cross-sectional side elevation of the lock, as it appears in its operative state, with a diagrammatic layout of the window sashes.

Fig. 2 is a front elevation of the lock shown in Fig. 1.

Fig. 3 is a side elevation of the lock shown in Fig. 1, with the lock shown as set in its inoperative state.

An upper window sash 1 and a lower window sash 2 are framed in guiding ways of the window-frame, not shown, whereby they are slidable upwardly and downwardly for opening or closing the window to any greater or lesser extent. The sash-lock 3 comprises a base 4 carrying a cam 5, which

is pivoted thereto by means of a rivet 6 passing through the cam and through two side-walls 7 forming part of the base. Said base comprises further a bottom wall 8, from which extend a pair of ears 9, and an upright front wall 10 having a tapped opening 11. The lock is fastened in place to the top-rail 12 of the lower window-sash 2, so that it is disposed adjacent and opposite to the upright rail 13 of the upper sash 1, and it is normally secured in its place by means of wood-screws, not shown, passing through openings 14 in the ears 9 and threading into the rail 12. Or, if it is desired to render this lock attachable and detachable, the ears 9 may be secured, by means of machine-screws 15 to an auxiliary plate 16, Figures 1, 2, which is in turn fastened to the top-rail 12 of the lower window-sash 2. Said plate comprises ears 17, having tapped holes 18 which register with the openings 14 for receiving said machine-screws, a downwardly projecting portion 19 at the front thereof having a tapped opening 20, and a downwardly projecting portion 21 at the rear thereof. A screw 22 threads through the opening 20 toward and away from the sash 2, whereby when it is tightened it binds forcibly the portion 21 against 85 the sash 2 and in this manner clampingly fastens the lock in required position. If therefore it is desired to mount the lock in its place, it merely requires placing the plate 16 over the top-rail 12 and tightening 90 the screw 22, and when it is desired to detach the lock, the screw 22 may be unthreaded and the plate 15 with the lock thereby removed. This means of rendering the lock detachable is particularly useful 95 for demonstration purposes.

The cam 5 is provided in its rear face with a channel 23 of dove-tailed cross-sectional configuration, within which is located a rubber plate 24, the face 25 of which is curved and eccentric to the fulcrum 6, about which the cam is swingable. Normally, therefore, the cam 5 bears by its own weight against the upright rail 13 of the upper sash, and thereby securely locks the sashes 1, 2 in any position, due to the cam-surface 25 binding against the upper sash and preventing downward movement thereof, as well as preventing upward movement of the lower sash, although permitting a relative or closing movement of either of the sashes in an opposite direction. To render the lock

inoperative the cam 5 may be swung about its pivot 6 to the position shown in Figure 3, in which position it will be maintained by its own weight and permit the free shifting of each of the sashes upwardly or downwardly. Should it be desired to effect a firmer initial grip of the cam 5 against the sash 1 and a more positive maintenance of the cam in its inoperative position shown in Fig. 3, a spring 26 may be provided which is secured at one end 27 to the cam 5 and at its opposite end 28 to the base 4. Said spring will therefore draw the cam 5 against the upper sash when the cam is in operative state, as shown in Fig. 1, and, after being stretched during the swinging of the cam away from the sash about its fulcrum, will similarly draw the cam against the apex of the wall 10 when the cam is in its inoperative state, as shown in Fig. 3.

In order to conveniently manipulate the lock to set its cam 5 in operative or inoperative state, a plunger 29 is provided, having a bead 30, a portion 31 of small diameter, a bead 32, a portion 33 similar to portion 31, a portion 34 adapted to thread into and out of the tapped opening 11, a portion 35 having a diameter similar to the inner diameter of the tapped opening 11, and a knurled knob 36. The boss 37 of the cam 5 is provided with teeth 38, which are adapted to cooperate with the annular shoulders 39 of the beads 30, 32 and portion 34 in a manner similar to a gear-and-rack action, said teeth acting as a form of gear and the plunger 29 acting as a form of rack. Said plunger is slidable longitudinally in the base 4 by means of its portion 35 being guided by the tap of the opening 11 in wall 10. Preferably, the plunger 29 is further guided in its longitudinal movement by its resting between a pair of guiding ribs 40 formed in the bottom-wall 8 of the base 4.

Should it be desired to set the lock in its inoperative state, for freely sliding the sashes for window cleaning, or for securing full ventilation, or other purposes, it merely requires pressing the plunger 29 forwardly, in a direction toward the sashes, whereupon its beads 30, 32, portion 34, and the shoulders of the latter will mesh with the teeth 38 and cause the cam to be disposed to its inoperative position shown in Fig. 3; and should it be desired to set the lock back to its operative state, it merely requires withdrawal of the plunger 29, whereupon the opposite action will take place and the cam 5 will be restored to the position shown in Fig. 1, in operative engagement with the upper sash 1. In this longitudinal movement of the plunger 29 the knob 36 and portion 34 act as abutments or stops therefor at either end of its stroke.

In this type of sash-lock an objection sometimes met with is that the intruder may

insert a stick through the partially opened upper sash and therewith release the cam from the sash. Should it be desired to avoid such possible manipulation, when utilizing this lock, it merely requires turning of the plunger 29 so as to thread its portion 34 into the tapped opening 11, whereupon the shoulder 39 of bead 30 will bear against the lower tooth 38 and thereby cause the cam 5 to be firmly locked in its binding engagement with the sash 1.

It will be evident that this sash-lock will carry out all of its above described functions efficiently, and that it is possessed of a number of other important advantages.

Variations may be resorted to within the scope of the invention, and portions of the improvements may be used without others.

Having thus described my invention, I claim:—

1. A sash lock having the combination of a base adapted to be secured to the lower window-sash, a cam fulcrumed on said base adapted to frictionally engage the upper sash, and a plunger guided by said base to move longitudinally and to actuate said cam to throw it out of its operative state.

2. A sash lock having the combination of a base adapted to be secured to the lower window-sash, a cam fulcrumed on said base adapted to frictionally engage the upper sash, said base having a tapped opening and a plunger guided by said tapped opening to move longitudinally without rotation and to throw said cam into operative state.

3. A sash lock having the combination of a base adapted to be secured to the lower window-sash, a cam fulcrumed on said base adapted to frictionally engage the upper sash, and a plunger guided by said base to move longitudinally and to actuate said cam to throw it into and out of its operative state.

4. A sash lock having the combination of a base adapted to be secured to the lower window-sash, a cam fulcrumed on said base adapted to frictionally engage the upper sash, a plunger guided by said base to move longitudinally and to actuate said cam to throw it out of its operative state, said cam adapted to remain in inoperative state, and said plunger adapted to throw said cam from inoperative into operative state.

5. A sash lock having the combination of a base adapted to be secured to the lower window-sash, a cam fulcrumed on said base adapted to frictionally engage the upper sash, and a rod threading through said base having means to actuate said cam and lock it in its operative state by the threading action of said rod in a direction away from said sashes.

6. A sash lock having the combination of a base adapted to be secured to the lower window-sash, a cam fulcrumed on said base

adapted to frictionally engage the upper sash, said base having a tapped opening, a plunger guided by said tapped opening to move longitudinally without rotation and to 5 actuate said cam to throw it out of its operative state, and said plunger threading through said tapped opening and actuating said cam to lock it in its operative state by said threading action.

10 7. A sash lock having the combination of a base adapted to be secured to the lower window-sash, a cam fulcrumed on said base adapted to frictionally engage the upper sash, said base having a tapped opening, a 15 plunger guided by said tapped opening to move longitudinally without rotation and to throw said cam into operative state, and said plunger threading through said tapped opening and actuating said cam to lock it 20 in its operative state by said threading action.

8. A sash lock having the combination of a base adapted to be secured to the lower window-sash, a cam fulcrumed on said base 25 adapted to frictionally engage the upper sash, a plunger guided by said base to move longitudinally and to actuate said cam to throw it into and out of its operative state, and said plunger threading through said 30 base and actuating said cam to lock it in its operative state by its threading action.

9. A sash lock having the combination of a base adapted to be secured to the lower window-sash, a cam fulcrumed on said base 35 adapted to frictionally engage the upper sash, a plunger guided by said base to move longitudinally and to actuate said cam to throw it out of its operative state, said cam adapted to remain in inoperative state, 40 said plunger adapted to throw said cam from said inoperative into operative state, and said plunger threading through said base and actuating said cam to lock it in its operative state by its threading action.

45 10. A sash lock having the combination of a base adapted to be secured to the lower window-sash, a cam fulcrumed on said base adapted to frictionally engage the upper sash, said base having a threaded opening, 50 a plunger slidable longitudinally through said opening actuating said cam to throw it out of its operative state, said cam adapted to remain in inoperative state, said plunger adapted to throw said cam from said 55 inoperative into operative state, and said plunger threading through said opening and actuating said cam to lock it in its operative state by its threading action.

60 11. A sash lock having the combination of a base adapted to be secured to the lower window-sash, a cam fulcrumed on said base adapted to frictionally engage the upper sash, said base having a threaded opening, a plunger slidable longitudinally through 65 said opening actuating said cam to throw

it out of its operative state, said cam adapted to remain in inoperative state, said plunger adapted to throw said cam from said inoperative into operative state, and said plunger threading through said opening and actuating said cam to lock it in its operative state by its threading action in a direction away from said sashes. 70

12. A sash lock having the combination of a base adapted to be secured to the lower window-sash, a cam fulcrumed on said base adapted to frictionally engage the upper sash, said base having a threaded opening, a plunger slidable longitudinally through said opening without rotation actuating said cam to throw it out of its operative state, said plunger throwing said cam into operative state, and said plunger threading through said opening and actuating said cam to lock it in its operative state by its threading action. 75 80

13. A sash lock having the combination of a base adapted to be secured to the lower window-sash, a cam fulcrumed on said base adapted to frictionally engage the upper sash, said cam adapted to be disposed about its fulcrum in operative and in inoperative positions, said cam adapted to be held in either of said positions by its own weight, and a plunger guided by said base to move 90 longitudinally and to actuate said cam to throw it into either of said positions. 95

14. A sash lock having the combination of a base adapted to be secured to the lower window-sash, a cam fulcrumed on said base adapted to frictionally engage the upper sash, said cam adapted to be disposed about its fulcrum in operative and in inoperative positions, said cam adapted to be held in either of said positions by its own weight, and a plunger guided by said base to move longitudinally and to throw said cam out of said inoperative position and into said operative position. 100 105

15. A sash lock having the combination of a base adapted to be secured to the lower window-sash, a cam fulcrumed on said base adapted to frictionally engage the upper sash, said cam adapted to be disposed about its fulcrum in operative and in inoperative positions, said cam adapted to be held in either of said positions by its own weight, a plunger guided by said base to move longitudinally and to actuate said cam to throw it out of said operative position and into inoperative position, and said plunger throwing said cam out of said inoperative position and into said operative position. 110 115 120

16. A sash lock having the combination of a base adapted to be secured to the lower window-sash, a cam fulcrumed on said base adapted to frictionally engage the upper sash, said cam adapted to be disposed about its fulcrum in operative and in inoperative positions, said cam adapted to be held in 125 130

either of said positions by its own weight; a plunger guided by said base to move longitudinally and to actuate said cam to throw it out of said operative position and into 5 said inoperative position, said plunger throwing said cam out of said inoperative position and into said operative position and said plunger threading through said base and actuating said cam to lock it in 10 its operative state by its threading action.

17. A sash lock having the combination of a base adapted to be secured to the lower window-sash, a cam fulcrumed on said base adapted to frictionally engage the upper 15 sash, said cam adapted to be disposed about its fulcrum in operative and in inoperative positions, said cam adapted to be held in either of said positions by its own weight, and a rod threading through said base having 20 means to actuate said cam and lock it in its operative state by the threading action of said rod in a direction away from said sashes.

18. A sash lock having the combination 25 of a base adapted to be secured to the lower window-sash, a cam fulcrumed on said base adapted to frictionally engage the upper sash, said cam adapted to be disposed about its fulcrum in operative and in inoperative 30 positions, a spring holding said cam in either of said positions, and a plunger guided by said base to move longitudinally and to actuate said cam to throw it out of 35 said operative position and into said inoperative position.

19. A sash lock having the combination 40 of a base adapted to be secured to the lower window-sash, a cam fulcrumed on said base adapted to frictionally engage the upper sash, said cam adapted to be disposed about its fulcrum in operative and in inoperative 45 positions, a spring holding said cam in either of said positions, and a plunger guided by said base to move longitudinally and to throw said cam out of 50 said inoperative position and into said operative position.

20. A sash lock having the combination 55 of a base adapted to be secured to the lower window-sash, a cam fulcrumed on said base adapted to frictionally engage the upper sash, said cam adapted to be disposed about its fulcrum in operative and in inoperative 60 positions, a spring holding said cam in either of said positions, a plunger guided by said base to move longitudinally and to actuate said cam to throw it into and out of either of said positions.

21. A sash lock having the combination 65 of a base adapted to be secured to the lower window-sash, a cam fulcrumed on said base adapted to frictionally engage the upper sash, said cam adapted to be disposed about its fulcrum in operative and in inoperative 70 positions, a spring holding said cam in either of said positions, a plunger guided by said base to move longitudinally and to actuate said cam to throw it into and out of either of said positions, and said plunger threading through said base and actuating 75 said cam to lock it in its operative state by its threading action.

22. A sash lock having the combination of a base adapted to be secured to the lower window-sash, a cam fulcrumed on said base 80 adapted to frictionally engage the upper sash, said cam adapted to be disposed about its fulcrum in operative and in inoperative positions, a spring holding said cam in either of said positions, and a rod threading 85 through said base having means to actuate said cam and lock it in its operative state by the threading action of said rod in a direction away from said sashes.

23. A sash lock having the combination 90 of a base adapted to be secured to the lower window-sash, a cam fulcrumed on said base adapted to frictionally engage the upper sash, and a plunger guided by said base to move longitudinally having an annular 95 shoulder adapted to engage and actuate said cam to throw it out of its operative state.

24. A sash lock having the combination of a base adapted to be secured to the lower window-sash, a cam fulcrumed on said base 100 adapted to frictionally engage the upper sash, and a plunger guided by said base to move longitudinally having an annular shoulder adapted to engage and throw said cam into operative state.

25. A sash lock having the combination 105 of a base adapted to be secured to the lower window-sash, a cam fulcrumed on said base adapted to frictionally engage the upper sash, and a rod threading through said base having an annular shoulder adapted to engage and actuate said cam to lock it in its operative state by the threading action of said rod.

26. A sash lock having the combination 110 of a base adapted to be secured to the lower window-sash, a cam fulcrumed on said base adapted to frictionally engage the upper sash, said base having a threaded opening, 115 a plunger slideable longitudinally through said opening having annular shoulders adapted to engage and throw said cam into and out of operative states, and one of said shoulders locking said cam in its operative state by the threading action of the plunger.

27. A sash lock having the combination of a base adapted to be secured to the lower window-sash, a cam fulcrumed on said base adapted to frictionally engage the upper 125 sash, and means for detachably securing said base to the lower window-sash including an auxiliary plate, means to secure said base to said plate, and means to secure said plate to said lower sash.

28. A sash lock having the combination 130

of a base adapted to be secured to the lower state, and said base having auxiliary means window-sash, a cam fulcrumed on said base to guide said plunger laterally. Signed at the city of New York, in the 10
adapted to frictionally engage the upper sash, said base having a tapped opening, a county of New York, and State of New
5 plunger guided by said opening to move longitudinally being adapted to actuate said York, this 8th day of June, A. D. 1923.

BENJAMIN ROMAN.
